ENGINE

Archie M. Niven, Detroit, Mich., assignor to Continental Motors Corporation, Detroit, Mich., a corporation of Virginia

Application October 31, 1930. Serial No. 492,493

3 Claims. (Cl. 123—81)

My invention relates to internal combustion engines and more particularly to that type of engine provided with one or more sleeve valves, although I wish it understood that the principles 5 of my invention may be embodied in engines other than those of the sleeve valve type.

In internal combustion engines and especially engines of the sleeve valve type, it is necessary to disassemble the engine at certain times in 10 order that repairs or adjustments may be made, or to permit the replacement of worn parts. One of the difficulties in servicing engines, where the above disassembly is necessary, is the reassembly of the engine in such a way that the valve mechanism 15 will be correctly timed with respect to the crankshaft. It is also difficult in the initial assembly of the engine to correctly time the valve mechanism with respect to the crankshaft. Various marking devices and means have been 20 generally employed for indicating the position of the valve operating mechanism or valve shaft so that the same can be positioned in predetermined relation with respect to the crankshaft, but these methods depend principally upon the 25 keenness and ability of the mechanic for obtaining an accurate timing between the valve operating mechanism and the engine crankshaft, and often the engine is not timed accurately because of the carelessness on the part of the 30 mechanic. In a four stroke cycle engine in which the valveshaft rotates at one half crankshaft speed there are two positions of the crankshaft at which the markings on the gears will coincide, thus care must be exercised in selecting the correct 35 crankshaft position on assembly of the engine.

An object of my invention is to provide a novel engine structure wherein the timing of the valve operating mechanism and the crankshaft may 40 be accurately obtained in the initial assembly or reassembly of the engine structure by providing a valve operating mechanism that is preferably carried by the cylinder block in such a way that the valve driving mechanism and the 45 valve may be positioned in predetermined timed position with respect to each other, said valve driving mechanism being adapted for operative connection with the engine crankshaft on assembly of the engine block and crankcase. 50 Another object of my invention is to provide a novel engine structure employing a valve operating mechanism that is carried by the engine block wherein a coupling means is interposed between the valve operating mechanism and the 55 crankshaft, which is constructed for operative

assembly only when said valve operating mechanism and crankshaft are relatively positioned in their proper predetermined timed relation.

Further features and objects of my invention relate to the novel coupling means positioned intermediate the valve operating mechanism and the crankshaft, thereby providing an engine assembly that may be readily and economically manufactured and which can be more readily serviced with a minimum of time and labor. 60

For a more detailed understanding of my invention, reference may be had to the accompanying drawings which illustrate one form which my invention may assume, and in which:

Figure 1 is a vertical transverse sectional view 70 through an internal combustion engine of the sleeve valve type illustrating a valve operating mechanism and driving means therefor constructed in accordance with my invention.

Figure 2 is a horizontal plan sectional view 75 taken substantially on the line 2—2 of Figure 1.

Figure 3 is a fragmentary distended perspective view illustrating a portion of the valve operating mechanism such as a valveshaft or layshaft, a coupling and a portion of the layshaft 80 driving means.

Figure 4 is a fragmentary elevational view of a portion of the coupling, and

Figure 5 is a detail sectional view taken on the line 5—5 of Figure 4. 85

I have chosen for purposes of illustration, a sleeve valve engine comprising a cylinder block 10 having cylinders 9 and the usual water jacket 11 and a reentrant cylinder head 12 secured to the cylinder block and depending within the cylinders 9 in spaced relation therewith to provide a sleeve pocket 13 for accommodating one or more sleeve valves. A sleeve valve 14 in the embodiment shown is movably supported within the cylinders and projected into its sleeve pocket 13, 95 this sleeve valve being ported for intake and exhaust and moved with a combined reciprocating and oscillating movement with respect to the sleeve and cylinder axes.

A crankcase 15 is secured beneath the cylinder 100 block 10 and is preferably constructed to house the valve operating mechanism 16 and the crankshaft 17, said crankshaft being supported by any suitable type of bearings carried by the crankcase. A piston 8 is operatively supported within the 105 cylinder and sleeve valve and is connected with the crankshaft by a standard connecting rod 7. A gear 18 is secured to one end of the crankshaft and engages a gear 19 of larger diameter that is keyed or otherwise secured to a layshaft driving 110

means or driving shaft 20, thereby providing means for driving the layshaft driving means at one-half crankshaft speed for a four stroke cycle engine.

5 As illustrated in the accompanying drawings, I have provided a layshaft 21 supported with the cylinder block 10 by suitable spaced bearings 22 carried by the brackets 5 preferably secured to the underside of the cylinder block as illustrated in 10 Figure 1. The layshaft is thus positioned in parallel relation to the crankshaft axis and offset to one side of the cylinders, said layshaft being provided with spaced cranked portions 33 to which are attached the sleeve driving links 24 for imparting a combined oscillating and reciprocating movement to the sleeve valve 14. Other known types of sleeve driving means may be employed if desired as the specific form of sleeve driving links and associated parts does not in itself form 15 the subject matter of this invention.

20 A coupling means is preferably positioned intermediate the layshaft 21 and the layshaft driving means 20, this layshaft driving means being preferably supported in a bearing 25 carried by the 25 crankcase and is preferably axially aligned with the layshaft axis. The coupling means A which I find very suitable for my purpose is known as an "Oldham" coupling, in its fundamental parts and which comprises a pair of members 26 and 27 30 that are provided with a groove and tongue 28 and 29 respectively. The tongue is adapted to slide in the groove and the member 27 carrying the tongue is preferably carried by the layshaft while the member 26 carrying the groove is preferably carried by the layshaft driving means, the 35 member 26 being adapted to be secured to the layshaft driving means by a tongue and groove connection 30 and the screws 30—a which are projected through the elongated slots 31 in the member 26 and engaged in the internally threaded 40 holes 32 carried by the end of the layshaft driving means 20.

45 Since the layshaft is journaled at spaced intervals to the cylinder block by means of the supports or brackets 5, the said layshaft may be bodily removed with the cylinder block, and separated from the layshaft driving means carried by the crankcase. On disassembling the engine, i. e., 50 relatively separating the cylinder block and crankcase, it will be noted that the tongue 29 carried by one part of the coupling merely slides out of the groove 28 carried by the other part of the coupling, thereby disconnecting the layshaft from the layshaft driving means. In order to assemble 55 the engine together so that the layshaft will be positioned in proper predetermined timed relation with respect to the crankshaft, I have provided means whereby the members of the coupling device may be operatively assembled together in only one position. This is accomplished 60 by providing end plates 40 and 41 carried respectively on the members 26 and 27 thereby permitting the tongue 29 to slip in the groove 28 in only one direction. Proper timing of the engine is 65 thus insured because of the fact that the valve operating mechanism and the driving means therefor can be operatively assembled only when the said layshaft or valve operating mechanism and layshaft driving means are positioned in their proper predetermined timed relation.

70 Since the gears 18 and 19 provide a speed re-

ducing means driving the layshaft driving means 20 at one-half crankshaft speed, the coupling device may be thus adapted to connect the layshaft with the layshaft driving means in direct driving relation.

80 It will be noted that I have provided a novel engine construction in which a simple coupling device is employed for connecting the valve operating mechanism with the driving means, said coupling means being axially aligned therewith and releasable on relative separation of the engine block and crankcase, said coupling means being constructed so that the same can only be 85 reassembled when the layshaft and layshaft driving means are positioned in their proper predetermined timed relation, thereby avoiding any likelihood of imperfect or haphazard workmanship in reassembling the engine as the correct timing may be obtained independently of any effort on the part of the mechanic.

90 Although I have illustrated but one form of my invention and have described in detail but a single application thereof, it will be apparent to those skilled in the art to which my invention pertains that various modifications and changes may be 95 made therein without departing from the spirit of my invention or from the scope of the appended claims.

95 What I claim as my invention is:

100 1. In a multi-cylinder internal combustion engine of the sleeve valve type having a crankshaft, a crankcase and a cylinder block, the combination with a sleeve valve in each cylinder, of sleeve valve operating means supported on said block and including a layshaft, means supported by the crankcase and including a layshaft driving means operatively connected with said crankshaft and adapted for operative connection with said layshaft, for operating said layshaft at substantially one-half crankshaft speed, and coupling means 110 intermediate said layshaft and said layshaft driving means adapted to operatively connect same in but one predetermined timed relation.

115 2. In a multi-cylinder internal combustion engine of the sleeve valve type, a crankshaft, a layshaft carried by the cylinder block and operatively connected with the sleeve valve, driving means between the crankshaft and layshaft and including a reduction drive mechanism and a coupling device permitting relative separation of the 120 crankshaft and of the cylinder block with the layshaft and sleeve valve, said coupling device positioned intermediate the reduction drive mechanism and sleeve valve and constructed for operative assembly only when the crankshaft and layshaft are in a predetermined timed relation.

130 3. In a multi-cylinder internal combustion engine of the sleeve valve type, a crankshaft, a layshaft carried by the cylinder block and operatively connected with the sleeve valve, driving means between the crankshaft and layshaft and including a reduction drive mechanism and a coupling device permitting relative separation of the 135 crankshaft and of the cylinder block with the layshaft and sleeve valve, said coupling device positioned intermediate the reduction drive mechanism and layshaft and constructed for operative assembly 140 only when the crankshaft and layshaft are in a predetermined timed relation.

145 ARCHIE M. NIVEN.
